(No Model.)

G. WINHEIM.

ROLL PAPER HOLDER AND CUTTER.

No. 398,762.

Patented Feb. 26, 1889.

UNITED STATES PATENT OFFICE.

GUSTAV WINHEIM, OF CARLYLE, ILLINOIS, ASSIGNOR TO ABBOTT Q. ROSS,
OF CINCINNATI, OHIO.

ROLL-PAPER HOLDER AND CUTTER.

SPECIFICATION forming part of Letters Patent No. 398,762, dated February 26, 1889.

Application filed July 31, 1888. Serial No. 281,578. (No model.)

To all whom it may concern:

Be it known that I, GUSTAV WINHEIM, a citizen of the United States, residing at Carlyle, in the county of Clinton and State of Illinois, have invented certain new and useful Improvements in Roll-Paper Holders and Cutters; and I do hereby declare the following to be a full, clear, and exact description of the invention, such as will enable others skilled in the art to which it appertains to make and use the same.

This invention relates to wrapping-paper holders, and particularly to the kind in which a roll of paper is held in a standard or frame in such manner that it is capable of turning therein to deliver the paper, and in which a paper-cutter rests on the roll to facilitate severing pieces from the roll.

The object of the present invention is to produce a paper holder and cutter in which the cutter proper is so arranged as to bear constantly on the roll of paper by its own weight, and which is so constructed that the paper may be arranged to be drawn from either side of the device, as desired.

With these objects in view my invention consists, essentially, in a roll-paper holder and cutter comprising a frame of a paper-stand provided above the roll with vertical grooves or ways, and a paper-cutter, preferably of metal, mounted in slides and having its lower surface bearing directly on the paper, the bearing-surface being preferably concave, to present the cutting-edges at each side.

I have illustrated the invention in the accompanying drawings, in which—

Figure 1 is a perspective view of a paper-holder made in accordance with my invention, the roll and paper-cutter being shown in proper operative position. Fig. 2 is a side elevation of the device, one side being broken away and the roll being shown in dotted lines; and Fig. 3 is a sectional view of one of the standards.

In the drawings, A represents a base, to which are attached the uprights *a a*, supporting the roll and paper-cutter and forming the frame of the device.

I have in the present case shown a holder designed to receive three rolls of paper. Obviously, the frames may be constructed to re-

ceive any desired number of rolls. In each of the uprights *a* is cut an inclined groove, *a'*, which is designed to receive the end of a bar, *b*, passing through the roll and supporting the same, the bearing in the groove being of such form as to allow the bar, and consequently the roll placed on it, to revolve freely. In the center of each of the uprights *a* is an elongated groove, *a''*, and in this is inserted the reduced end *c* of the paper-cutter *C*.

The paper-cutter *C* is of metal or of some other suitable material, weighted, and is as large as it can conveniently be, in order to have as much weight as may be required to hold it upon the roll *B*, upon which it bears. The lower face of the paper-cutter is preferably channeled, as shown, to form sharp edges *b'*, which are always in contact with the roll and serve as cutters when the paper is drawn against it for the purpose of tearing off a piece.

As the paper is used and the roll diminishes in size, the paper-cutter will fall by its own weight and be constantly in contact with the surface of the roll and always ready for use.

The advantage of a holder in which a cutter having the springs is dispensed with and the weighted cutter substituted therefor will be clear at once, as by the improved frame adjustment of the parts to compensate for the change in the size of the roll is avoided, the cost of the device materially lessened, and the holder is rendered much more commodious in use.

I am aware that heretofore there has been combined with a paper-roll a gravitating cutter-bar having guides arranged at an angle to the plane in which the cutter-bar presses upon the roll, instead of in a plane parallel to said plane of pressure; but such prior construction is faulty, in that where an irregularly-shaped roll—that is to say, a roll slightly flattened or elliptical in contour—is employed (and a truly cylindrical roll can seldom be found on the market) there is a binding of the cutter-bar in the guides whenever the roll is attempted to be rotated. When the cutter-bar bears in a plane parallel to the plane of the guides, however, as in my invention, this tendency to bind does not exist and the

cutter-bar rides freely up and down whether the roll be true or elliptical.

Having thus fully described my invention, what I claim as new, and desire to secure by Letters Patent, is—

1. In a paper holder and cutter, the combination, with the roll of paper, of a weighted bar having a cutting edge or edges pressed by gravity against the periphery of said roll, and guides for the cutter-bar arranged in planes substantially parallel to the plane in which the cutter-bar presses against the roll, whereby binding of the cutter-bar is prevented during its up and down movements,

due to any irregularity in the contour of the roll, substantially as described.

2. In a paper holder and cutter, the frame having the vertical grooves or ways and the paper-cutter consisting of the bar of metal mounted in the grooves, provided with the lower concave face, and bearing on the roll, substantially as described.

In testimony whereof I affix my signature in presence of two witnesses,

GUSTAV WINHEIM.
